UNITED STATES PATENT OFFICE

ALAN C. CRAGO, DECEASED, LATE OF PITTSBURGH, PENNSYLVANIA, BY SAMUEL D. CRAGO, ADMINISTRATOR, OF PITTSBURGH, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed August 29, 1927. Serial No. 216,032.

The invention relates to circuit-interrupting devices and particularly to arc extinguishing means for use in connection therewith.

5 The principal field for immediate application of the invention is in connection with alternating current circuit breakers, and there will be hereinafter described an embodiment of the invention as applied to such 10 circuit breakers without in any way intending to restrict the scope of the invention, except as indicated in the appended claims.

One object of the invention is to provide means for interrupting the flow of electricity 15 through a gaseous medium.

Another object of the invention is to provide a circuit breaker with an arc-interrupting device capable of opening high voltage, large current arcs in air or gas without recourse to oil or other arc quenching media. 20 In some of its aspects, however, the invention is applicable in connection with low power circuit interrupting devices and to a variety of other uses.

25 Another object of the invention is to provide a structure wherein an arc may be operated in proximity to metallic deionizing means without being split up into a plurality of short sections operating from cathodes 30 on the metallic members.

A further object of the invention is to provide a deionizing chamber for circuit interrupters comprising a plurality of metallic rods so arranged that an arc can be forced to 35 operate in the interstices between them without destructive melting of the metallic members.

Further objects of the invention will be 40 come apparent through reading the following description taken in connection with the drawings wherein:

Figure 1 is a view in elevation, partly in section, of a circuit interrupting device embodying the deionizing structure of the invention.

Fig. 2 is a sectional view taken on the lines from II-II of Fig. 1,

Fig. 3 is an enlarged plan view of the interrupting device shown in Fig. 1,

Fig. 4 is a diagram illustrating certain circuit connections employing the invention,

Fig. 5 is a diagram used in explaining the invention,

Fig. 6 is a similar explanatory diagram, 55

Fig. 7 is a detail of one form of an element of the deionizing structure embodying the invention, and

Fig. 8 is a detail of another form of an element embodied in the deionizing structure 60 of the invention.

Patent 1,819,207, issued Aug. 18, 1931, on an application of Joseph Slepian, assigned to the Westinghouse Electric & Manufacturing Co. describes a circuit breaker provided 65 with a deionizing structure which extinguishes the arc incident to the opening of its main contact, this deionizing structure comprising a series of sheets of metallic gauze through the openings of which the arc is 70 compelled to run, and by which the arc path is rapidly deionized at the instant when the main current falls to zero in its alternating current cycle.

While deionizing structures of this type 75 have been, in general, found to be eminently satisfactory, certain conditions of line voltage, frequency and current may exist in which the arc has been found to cease to operate in the interstices of the gauze and to split up 80 into a series of short arcs between successive gauze sheets.

Figure 5 diagrammatically illustrates such a breaking up of the arc into a series of short sections. Each of these short arcs has a 85 cathode and an anode on the wire gauze and these may cause a melting of the metal, and a destruction of the sheet thereby. In Fig. 5 the arc plays between arc terminal members 35 and 36 between which are placed wire 90 gauze sheets 37, as disclosed in the patent referred to above. In such a structure, under some conditions, the arc may be split up into short sections such as shown at 38a, 38b, and 38c, etc. The path of the current would 95 then be, for example, from terminal 35, through arc section 38a to gauze sheet 37a and then in the sheet 37a to the terminal of arc section 38b which conducts the current to sheet 37b. The current then flows in sheet 100

37b to the terminal of arc section 38c and so on through the remaining arc sections and sheets to the arc terminal member 36. This means that the total arc current will be flowing vertically in the sheets and must transfer from each sheet to the arc sections playing thereon. This transfer of the current from the sheets to the arc sections makes it possible for a hot cathode to form at one terminal of each arc section and an anode at the other terminal with a resulting burning of the gauze sheets, unless the arc is moved quite rapidly.

In accordance with the invention, breaking up of the arc into short sections with the consequent destruction of the deionizing sheets is prevented by substituting for the metal gauze of the patent referred to above, a structure comprising a series of parallel metal rods 25 which are interconnected at their ends through members 26 of high resistance. If the arc were to break up into a series of short lengths running between successive sets of these metal bars, current could not flow directly up or down in any given vertical row of bars 25a, 25b, or 25c, since there are no vertical cross conductors as when wire gauge is used, so that the current could only flow through the series of short arcs by passing from a rod in one horizontal row to a rod in another horizontal row through the end connections 26. Since these latter are of high resistance there must be a considerable voltage drop through this resistance and it is consequently more difficult for the arc to operate in a series of short arcs interconnected by this high resistance than it is for it to operate as a single long arc 39, such as that illustrated in Fig. 6, in a path confined to air spaces between the rods. The conducting bars 25 thus provide conducting paths across the arc extinguishing chamber only in a direction which is both transverse to the length of the arc and transverse to the direction of movement of the arc. This makes it more difficult for the arc to be split up into short arcs as it is moved into the conducting elements and avoids the formation of thermionic cathodes which would cause burning of the conducting elements at the base of each short arc.

Referring to the drawings, the circuit breaker in which the invention is here embodied comprises a pair of main contact members 1 and 2 arranged to be bridged by a contact brush 3 held upon a main contact arm 4. The arm is pivoted to swing the brush between the position in which it bridges the main contact members and the position away from said contact members in which the circuit breaker is opened.

The arm 4 is moved between its closed and open position by means of a link 5 and toggle mechanism of a design too well known in the art to require extended description here.

The circuit breaker is further provided with an arc interrupting structure 6 comprising an arcing contact arm 7 having at its upper end an arcing contact shoe 8 to engage a stationary arcing contact member 9 for finally interrupting the circuit. The arcing shoe 8 and the stationary arcing contact member 9 are suitably connected as by means of conductors 11, 12 and 13, that include main blow-out windings 14 which are thus in parallel to the main contact members.

To open the circuit the main contact arm and the arcing contact arm are swung to the right, in Fig. 1 by means of the toggle mechanism and link 5, above mentioned. This linkage is so arranged that in opening the circuit breaker, the brush 3 is first lifted from the contact members thereby diverting the line current from the brush 3 into the shunting circuit through the arcing contact arm 7, arcing contact shoe 8, stationary contact member 9, conductors 11, 12 and 13, and blowout winding 14. Further movement of the linkage fully opens the circuit by swinging the arm 7 farther to the right thus bringing about disengagement of the arcing contact shoe 8 from the stationary arcing contact member 9 at their arcing tips.

A pair of auxiliary contact members 15 that are arranged to be opened somewhat later than the main contact members 1, 2, 3, but somewhat earlier than the main contact tips 8 and 9, are usually provided to relieve the main contact members of the arcing incident to the transfer of current from the main brush to the inductive shunt circuit which includes the blowout coil 14 and the arcing contact members 8 and 9. Contact arm 4 is connected near its hinge to contact member 2 through the previously mentioned flexible conductor 13 to complete a path through the contacts 1 and 2 from contact member 8 to contact member 9.

The arc extinguishing structure 6, to which the invention is principally directed comprises an arc chute which extends above the space where the arc is drawn between tips of the arcing contact members 8 and 9. The arc shoe comprises a pair of horn-like inclined arcing plates 16 and 17 to which the arc drawn between the arcing tips of the arcing contact members 8 and 9 is transferred by the action of the main blow-out magnet. The blow-out magnet comprises a laminated core 18 that is excited by the previously mentioned blow-out winding 14, and a pair of pole shoes 19 positioned on opposite sides of the arcing-horn plates 16 and 17. The upper ends of the inclined arcing horn plates are metallically connected to vertical arcing plates 21, 22 as shown by Fig. 1.

The pole shoes 19 and the vertical arcing plates 21, 22 thus define a straight rectangular chamber having at its lower end an upwardly-tapered arc entrance chamber 23 ex-

tending between the inclined arcing-horn plates 16, 17 and the lower portions of the pole shoes 19. The magnetic flux induced between the pole shoes has a direction transverse to the plane of Fig. 1 so that when the circuit breaker is opened and an arc is drawn between the arcing tips 8, 9, it is blown toward the inclined arcing-horns 16, 17 and then upwardly along the latter through the entrance chamber 23 until it reaches the straight portion of the arcing chamber.

The straight portion of the arcing chamber between the arcing plates 21, 22 is filled with a series of what may be termed sectionalized or "ladder" grids 24, each one comprising a series of parallel metal rods 25, the ends of which are fastened in side plates 26 of high resistance material; the magnitude of the resistance of the side plates will depend, in ways that will be obvious to those skilled in the art, on the voltage and current rating of the circuit breaker; but for most ordinary purposes, it will be found sufficient to proportion the side plates 26 so that the resistance intervening between successive bars 25 is about equal to that of a ten ampere arc of the same length in the atmosphere by which the bars are surrounded; that is to say the resistance may be about three ohms for an air breaker. Figs. 7 and 8 illustrate such ladder-grids in detail and Fig. 2 clearly shows their position in the deionizing chamber. As shown by Figs. 1 and 3, the entire horizontal length of the chamber is occupied by a series of these vertical ladder-grids. The thickness of the side plates 26 is such that the metallic bars 25 are separated from each other by equal spacings. Insulating strips 27 may be provided between the high resistance end members 26 of the adjacent grids to separate them electrically from each other. To obtain a material for the plates 26 having sufficiently high resistance, an insulating composition may be employed into which a small amount of lamp black has been introduced.

The chamber containing these ladder-grids is closed on its two vertical sides by plates 28 of insulating material but is left open at the top so that it is possible for the heated gases incident to the operation of the arc to pass out of the chamber vertically.

The deionizing structure thus constituted may conveniently be held together by through bolts 29 linking the end plates and compressing the ladder-grids into a unitary rigid structure.

One desirable modification of the simple structure just described consists in subdividing the deionizing chamber lengthwise by two metallic partitions 31, 32 as shown in the section in Fig. 1. As illustrated in Fig. 4, resistances may be shunted between two pairs of the metallic plates. One of these resistances may be of smaller value than the other.

As a consequence of this arrangement, the arc drawn between the arcing tips 8, 9 will be forced by the blow-out magnet into the deionizing chamber and will subdivide into three shorter sections. Just after the alternating current passes through zero, the voltage tending to reignite the arc will rise more slowly on the section which is shunted by the lower resistance and the arc will be permanently extinguished in this section at this time. The arcs in the remaining sections may reignite, but the current now is limited by the resistance shunting the section in which the arc is extinguished.

In a similar manner, that one of the remaining arcs which is shunted by the other resistance will be more readily extinguished than the arc in the section which is not so shunted. It will be extinguished, therefore, in its turn, leaving the current flowing through the two shunting resistors in series, and then through the arc in the remaining section. The effect of this considerable resistance in series with the arc is to decrease the current therein and to facilitate its extinction on the next passage of the alternating current through zero. When it is so extinguished the entire circuit is, of course, open.

By this expedient of interrupting the arc by a series of separate steps, it is possible to interrupt heavier currents than would be possible if the entire interrupting operation had to take place at a single instant.

The voltage necessary to maintain the arc in the grids, is very considerably greater than that necessary to maintain an arc of the same length and current in the open air. On this account it is sometimes difficult to blow the arc into the structure, since in spite of the magnetic field, a lower voltage may be able to maintain the arc just outside the grids than within them. It is also found that with greater spacing between the bars, the arc voltage in the grids is less, and the arc passes more easily into the grid structure. The arrangement of Fig. 8 has, therefore, been found to be of advantage in many instances, inasmuch as the spacing of the bars is there made greatest at the lower end of the grid thus facilitating the entry of the arc into the grids, and the spacing is made less and less with a corresponding increase of efficiency in deionization at the upper end of the grid where the arc is to be extinguished.

While this modification of the invention is of advantage in many cases, certain others arise in which this more elaborate structure is not warranted, and the simpler structure of Fig. 7 may then be employed with advantage.

The mode of operation of the circuit breaker will now be clear. Upon the opening of the main contacts, 1, 2, 3, the line current is transferred through the conductors 11, 12,

13 and blowout-magnet winding 14 to the arc-ing arm 7 and the arc-ing-horn 9. As the arc-ing arm moves further to the right, its tip passes the lower end of the arc-ing horn 9 5 and thereby draws an arc therefrom. Upon its still further movement to the right, the end of this arc is transferred from the arc-ing arm 7 to the other arc-ing horn 17 as the arc is blown upward in the arc-ing chamber 10 under the influence of the blow-out magnet. The deflecting action of this magnet on the arc causes it to travel upward along the arc-ing horns 16, 17 into the deionizing structure above described. There it is compelled to operate in the spaces between the rods of the ladder-grids, and the proximity of these metallic members tend to deionize such por-tions of the arcs as are in proximity thereto. 15

As soon as it has been forced into contact with the vertical metal partitions 31, 32, the arc is subdivided into three shorter sections as has already been described. The deflecting force of the blow-out magnet forces the arc continually upward through the deionizing 20 chamber, thereby preventing it from remain-ing at any one place long enough to destruc-tively overheat the bars of the ladder-grids. In the course of the alternating current cy-25 cle, the line current passes its maximum and decreases to the value zero. When it reaches this value the interior of the deionizing cham-28 ber is still conductive due to the presence therein of a large number of positive and neg-30 ative ions which constituted the current car-33 riers of the arc, and which momentarily remain free due to the high temperature of the gases constituting an arc path. How-ever, the metallic rods absorb the thermal 35 energy and take up the electrical charge from such ions as come in contact with them, and thereby rapidly deionize the space in their immediate neighborhood. As the alternating voltage starts to rise on the reverse half 40 cycle, it draws such free ions as may still remain uncombined in the arc path into con-tact with one or the other of the metal bars and immediately discharges them and effects 45 their rapid recombination. The metallic bars, therefore, rapidly deionize the arc path and may do this so rapidly that the alternating voltage is insufficient to produce an ap-50 preciable amount of ionization by collision. Accordingly the flow of current through the 55 arc never rises beyond a small leakage value and the circuit is effectively interrupted.

As has been stated, the expedient of sub-dividing the arc by three separate chambers, and the use of resistance shunts, makes it pos-60 sible that this electrical instability may occur in the chamber shunted by the lowest resistance although it does not occur in the unshunted chamber. By this expedient of extinguishing the arc in stages, total cur-65 rents which would be too great for a single

unshunted structure to effectively deionize can be successfully coped with.

The deionizing structure which has been described, therefore, renders it possible to cause deionization of arcs of large current 70 value without danger of transfer of the arc to the separate metallic members constitut-ing the grids and the consequent destruction thereof by overheating.

The entire deionizing structure which has 75 been described and its attendant magnet may be supported on insulators on a metallic frame work such as is common in the art of large circuit breaker construction. No de-tailed description of such a structure is nec-80 essary in view of its ordinary and obvious character.

While in accordance with the patent stat-85 utes the foregoing details of the practical embodiment of the invention have been given, 85 it is to be understood that many of these are merely illustrative and that variations from the precise form will be desirable in design-ing circuit interrupters for other voltages and currents than those specified above. 90

The principles which have been embodied in the circuit breaker interrupter are applic-95 able to many other purposes than those here described as will be evident to persons skilled in the electrical arts. It is desired, therefore, that the language of the accompanying claims shall be accorded the broadest construction of which it is reasonably susceptible and that the invention shall be limited only by what is explicitly stated in the claims and by the 100 prior art.

What is claimed is:

1. In an arc extinguishing device, an arc chamber substantially filled with a multiplicity of rods of conducting material, each of 105 said rods being spaced from all of the other of the rods in the arc chamber and being mounted by means providing a considerable resistance between each rod and each of the other rods adjacent thereto in any direction. 110

2. In an arc extinguishing device, an arc chamber having therein a plurality of rows of rods of conducting material, each of said rods being spaced from all of the other of the rods in the arc chamber and being mounted 115 by means interposing an impedance between adjacent rods in any direction at least equal to the impedance of an arc at 10 amperes in the atmosphere of said chamber and of the same length as the distance between adjacent 120 rods.

3. In combination, means to establish an arc, means forming an arc extinguishing chamber and having a multiplicity of sepa-rate conducting elements positioned therein 125 from adjacent the end of said chamber adj-a-acent said means to establish the arc to adj-a-acent the opposite end thereof, said conduct-ing elements providing conducting paths across the arc extinguishing chamber only 130

- from side to side, and the resistance between adjacent conducting elements in any direction being substantially more than three ohms. 70
- 5 4. In combination, means to establish an arc, means forming the side walls of an arc extinguishing device, a multiplicity of separate conducting elements extending between said side walls over a considerable area 75
- 10 thereof, said conducting elements being insulated from each other in all directions for the portion of their length between said side walls and having their ends supported by said side walls, and said means forming the 80
- 15 side walls providing considerable resistance between the ends of said conducting elements. 85
5. In combination, means to establish an arc, an arc extinguishing device, means for causing movement of the arc in said arc extinguishing device, and a multiplicity of conducting elements positioned in said arc extinguishing device at intervals spaced along the direction of movement of the arc, said 90
- 20 conducting elements extending only in a direction which is both transverse to the length of the arc and transverse to the direction of movement of the arc. 95
6. In combination, means for causing an arc, means for extinguishing the arc including a stack of grids each positioned in a plane substantially transverse to the arc, each of said grids including a pair of edge members and a plurality of conducting wires spaced 100
- 25 from each other and having their ends secured to said edge members, and the material of said edge members providing a resistance between adjacent wires at least as great as the resistance of a 10 ampere arc in air. 105
7. In combination, means to establish an arc and deionizing means comprising bars of conducting material transverse to the arc path and resistance means interposed between the adjacent ends of the bars, the spacing of said bars varying with their distance from said arc establishing means. 110
8. In combination, means to establish an arc and deionizing means comprising bars of conducting material transverse to the arc path and resistance means interposed between the adjacent ends of the bars, the spacing of the bars nearest said arc-establishing means being greater than that of the bars 115

farthest from said arc-establishing means.

9. In combination, means to establish an arc and a deionizing chamber containing bars of conducting material transverse to the arc path, means to interpose between adjacent bars a resistance of substantially more than three ohms, the spacing of the bars nearest said arc-establishing means being greater than that of the bars farthest from said arc establishing means. 120

10. In combination, means to establish an arc and deionizing means comprising conductors transverse to the arc path, the spacing of said conductors varying with their distance from said arc-establishing means. 125

11. In combination, means to establish an arc, deionizing means comprising conductors transverse to the path of said arc, means to move the arc across said conductors, the spacing of said conductors varying with their distance from said arc establishing means. 130

12. In combination, means to establish an arc, deionizing means comprising conductors transverse to the path of said arc, means to impel the arc towards said conductors, the spacing of the conductors nearest said arc establishing means being greater than that of the conductors farthest therefrom. 135

13. In combination, means to establish an arc, deionizing means comprising conductors transverse to the path of said arc, resistance means interposed between the adjacent ends of the conductors, means to move the arc across said conductors, the spacing of said conductors varying with their distance from said arc establishing means. 140

14. In combination, means to establish an arc, deionizing means comprising conducting bars transverse to the path of said arc, resistances of substantially more than three ohms interposed between the adjacent ends of the bars, and means to deflect the arc towards said bars, the spacing of said bars varying with their distance from said arc establishing means. 145

In testimony whereof, I have hereunto subscribed my name this 18th day August, 1927.

SAMUEL D. CRAGO,
*Administrator of the Estate of Alan C.
Crago, Deceased.*
